UNITED STATES PATENT OFFICE.

OLIVER CARPENTER, OF OAKLAND, CALIFORNIA.

RUBBER-DAM CLAMP.

SPECIFICATION forming part of Letters Patent No. 354,391, dated December 14, 1886.

Application filed September 9, 1886. Serial No. 213,180. (No model.)

To all whom it may concern:

Be it known that I, OLIVER CARPENTER, of 5
Oakland, Alameda county, State of California,
have invented an Improvement in Rubber-
Dam Clamps; and I hereby declare the follow-
ing to be a full, clear, and exact description of
the same.

My invention relates to operative dentistry,
and particularly to the class of clamps which
10 are used for holding rubber dams in place
around the tooth.

My invention consists in a novel jointed
frame, carrying in its ends the separate and
removable jaws, and a set-screw, by which the
15 jaws are made to clamp tightly on the tooth,
all of which I shall hereinafter fully describe.

The object of my invention is to provide a
simple and effective rubber-dam clamp which
20 may be applied, by reason of its separate re-
movable jaws, to any of the ten anterior teeth
in each jaw, for the purpose of holding the
rubber dam back from the labio-cervical cavi-
ties in said teeth while filling such cavities, or
25 which may be applied in other suitable posi-
tions.

Referring to the accompanying drawings for
a more complete explanation of my invention,
Figure 1 is a perspective view of my rubber-
dam clamp. Fig. 2 is a view showing its ap-
30 plication.

The frame A, which is made somewhat of a
horseshoe shape, consists of two parts or sides
jointed together at a. The ends of these sides
are bent, and have secured in them the oppo-
35 sing jaws B. These are separate from the frame,
and consist of flat pieces of metal, the free ends
of which are filed, so as to fashion them to the
exterior surface of the tooth upon which they
are intended to fit.

40 The particular shape of the ends of the jaws
depends upon the teeth which they are to fit,
and I may therefore have a number of jaws
previously fashioned to approximately the
curvature of the various teeth, and may then
45 file them down to suit the case, either while
in the frame or before being inserted. To
readily accomplish this fitting of the jaws to
the several positions in which they are used, I
provide that their connection with the frame
50 A shall be a removable one, so that such jaws

may be used as any given case requires. In
this my invention differs essentially from the
ordinary curved clamps at present in use, and
which consist of a single piece of spring metal
having its ends adapted to fit but a single tooth,
55 and so highly tempered as to render it an im-
possibility to file them down to fit other teeth.
This connection between the jaws and the
frame, though it may be of any character
adapting them to be readily removed and re-
60 placed by others, I prefer to make in the fol-
lowing manner:

The ends of the sides of the frame are pro-
vided with slits, into which the jaws are slipped,
and are secured in their seats by means of the
65 screws b. A set-screw, C, passes through the
frame from side to side, being threaded in one
side, and playing loosely in a slot in the other
side, thus providing for the expansion or con-
traction of the parts of the frame. As I have
70 heretofore mentioned, the clamp is intended
more particularly for use in keeping the rub-
ber dam back from the labio-cervical cavities
of the ten anterior teeth in each jaw while fill-
ing such cavities. On account of the position
75 of these cavities, it is very difficult to keep the
edge of the rubber dam back. It is usually
done at present by means of the spring-clamps,
to which I have heretofore referred, the use
80 of which, in many cases, is uncertain, because
of their tendency to spring from position, as
they do not fit the teeth perfectly.

The application of my clamp is shown in
Fig. 2, where the clamp is seen in position
upon the tooth D, and is holding the rubber
dam E back. By reason of the previous prep-
aration of the ends of the opposing jaws they
85 fit accurately the tooth, and when the frame
is set up by means of the screw C they bind
firmly and accurately upon said tooth, and the
clamp has no tendency whatever to spring from
90 place.

Having thus described my invention, what I
claim as new, and desire to secure by Letters
Patent, is—

1. A rubber-dam clamp comprising the
curved hinged frame A, the jaws B in the
slotted ends of said frame, and the set-screw
C, by which said frame is expanded and con-
tracted, substantially as herein described. 100

2. A rubber-dam clamp comprising the hinged frame A, having slits in its ends, the jaws B, inserted in said slits and secured by the screws b, said jaws having their free ends 5 fashioned to the surface of the tooth to which they are fitted, and the screw C, by which the frame is expanded and contracted, substantially as herein described.

In witness whereof I have hereunto set my hand.

OLIVER CARPENTER.
